UNITED STATES PATENT OFFICE.

WILLIAM A. GRIFFITH, OF RACINE, WISCONSIN.

END-BOARD FASTENING FOR WAGON-BOXES.

SPECIFICATION forming part of Letters Patent No. 247,820, dated October 4, 1881.

Application filed February 17, 1881. (No model.)

To all whom it may concern:

Be it known that I, WILLIAM A. GRIFFITH, of Racine, in the county of Racine and State of Wisconsin, have invented certain new and useful Improvements in End-Board Fastenings for Wagon-Boxes, of which the following, in connection with the accompanying drawings, is a specification.

In the drawings, Figure 1 is a perspective 10 of a wagon-box provided with end-board fastenings embodying my invention. Fig. 2 is a perspective of the part of the fastening detached. Fig. 3 is a side view of the box with the fastening attached; Fig. 4, a top view 15 thereof, and Fig. 5 an end view.

Like letters of reference indicate like parts. A represents the box of a wagon.

B is the end-board or tail-board of the box A, and B' B' are the side-boards. The board 20 B is removable and adapted to slide vertically between the rear portions of the boards B' B'.

C C are cuts or deep notches made vertically in the boards B' B' and arranged opposite or adjacent to the vertical edges of the board B. 25 D D are lugs applied to the board B, and arranged to enter and project laterally beyond the cuts C C when the board B is in its place, as shown.

E E are bevel-headed spring catches or hooks 30 applied to the boards B' B', and arranged to engage the lugs D D, so as to hold the board B properly in its place. This engagement occurs automatically as the tail-board is pushed downward to its seat. To release the tail-board 35 it is only necessary to push the hooks E E away

from their engagement with the lugs D D. The tail-board may then be removed by being raised out from between the side-boards. The lugs D D, passing as they do through the openings C C, prevent the side-boards from being spread 40 apart; but it is not absolutely essential that the lugs should be T-shaped, as shown, for that purpose, for the same result will follow if the outer ends of the lugs project in only one direction, so as to engage the side-boards. 45 Neither is it essential that the inner ends of the lugs should be constructed precisely as shown, though I deem that form preferable.

It may be desirable to bind or guard the side-boards near the cuts C C, and in such 50 cases I propose to use the plates a a. Only one hook need be employed.

These parts may be furnished to the trade as fixtures, to be used for the purposes set forth.

Having thus described my invention, what I claim as new, and desire to secure by Letters Patent, is—

1. The herein described fixtures for fastening tail-boards, consisting of the lugs D D and 60 hooks or catches E E, substantially as and for the purposes specified.

2. The combination of the removable board B, the notched boards B' B', the lugs D D, and one or more catches or hooks, E E, substantially as and for the purposes specified.

WILLIAM A. GRIFFITH.
